UNITED STATES PATENT OFFICE.

WILLIAM M. MANN, OF HELENA, MONTANA TERRITORY.

GIRTH ATTACHMENT FOR SADDLE-TREES.

SPECIFICATION forming part of Letters Patent No. 253,401, dated February 7, 1882.

Application filed September 17, 1881. (No model.)

To all whom it may concern:

Be it known that I, WILLIAM MADISON MANN, of Helena, in the county of Lewis and Clarke, Montana Territory, have invented a new and useful Improvement in Girth Attachments for Saddle-Trees; and I do hereby declare that the following is a full, clear, and exact description of the same, reference being had to the accompanying drawing, forming part of this specification, in which the figure is a side elevation of my improved girth attachment for saddle-trees.

My invention relates to improvements in that class of girth attachments to saddle-trees in which two leather straps provided with girth-rings at their ends are wrapped, one around the horn and the other around the cantle of the tree. In this construction the rings on each side of the tree are connected together by straps, and the opposite rings, hanging down on each side of the tree, are connected by two girths passing under the belly of the horse. This construction of saddle is used by herders on the western plains, and is objectionable, as the cumbrous leather straps are in the way of the rider, and the one wrapped around the horn of the saddle becomes quickly worn through by the lasso wrapped around the horn of the saddle and the leather strap.

To remedy these defects is the object of my invention; and to this end it consists in dispensing with the leather straps wrapped around the horn and cantle of the saddle and substituting therefor, on each side of the tree, two forked or bifurcated metallic straps riveted, screwed, or otherwise secured to the tree, and not extending over the horn or cantle. The metallic straps carry the usual rings for the girths, and are connected together on each side by a leather strap, as hereinafter more fully set forth.

In the accompanying drawing, A represents a saddle-tree of the usual construction. On each side of the saddle-tree, near its ends and opposite each other, are secured by rivets, screws, or other suitable fastenings, the metallic forked or bifurcated straps *a a*. The metallic forked straps *a a* do not extend over the saddle-tree; so that the horn of the saddle is left entirely free for wrapping the lasso around it, and each forked metallic strap carries a ring, *b*, at its lower end, the rings *b* on each side of the tree lying opposite each other. The rings on each side are connected together by a leather strap, *c*. The girths *d d* are attached to the rings *b b* on one side of the tree, pass thence under the belly of the horse, and are secured to the opposite rings *b b* on the other side of the saddle-tree in the usual manner. This construction is cheaper and more durable than the usual one, the forked straps acting as braces, and the leather straps wrapped around the horn and cantle, inconveniencing the rider, are dispensed with and the horn left entirely free for wrapping the lasso around it.

I claim as my invention—

1. The combination, with a saddle-tree, of the forked metallic straps *a a*, secured to the tree near its ends and on each side thereof, and provided with rings *b b* at their ends, substantially as described.

2. The combination, with the saddle-tree A, of the forked metallic straps *a a*, secured to the tree, as set forth, and not extending as high as the horn of the tree, rings *b b*, straps *c*, and girths *d d*, substantially as described, and for the purpose set forth.

WILLIAM MADISON MANN.
